CLAIM

The ornamental design for a user interface module for electromedical apparatus, as shown and described.

DESCRIPTION

FIG. 1 is a front elevational view of a user interface module for electromedical apparatus;

FIG. 2 is a rear elevational view of the user interface module for electromedical apparatus of FIG. 1;

FIG. 3 is a top plan view of the user interface module for electromedical apparatus of FIG. 1;

FIG. 4 is a bottom plan view of the user interface module for electromedical apparatus of FIG. 1;

FIG. 5 is a right side elevational view of the user interface module for electromedical apparatus of FIG. 1;

FIG. 6 is a left side elevational view of the user interface module for electromedical apparatus of FIG. 1; and,

FIG. 7 is a perspective view from a direction between the front and right side of the user interface module for electromedical apparatus of FIG. 1.
